UNITED STATES PATENT OFFICE.

ROBERT DICK, OF GREENHEAD, GLASGOW, COUNTY OF LANARK, SCOTLAND.

BELTING.

SPECIFICATION forming part of Letters Patent No. 401,642, dated April 16, 1889.

Application filed July 9, 1887. Serial No. 243,901. (No model.) Patented in England October 14, 1885, No. 12,253, and June 25, 1887, No. 9,043.

To all whom it may concern:

Be it known that I, ROBERT DICK, a subject of the Queen of Great Britain and Ireland and residing at Greenhead, Glasgow, in the county of Lanark, Scotland, have invented certain Improvements in Ropes or Round Bands, (for which I have obtained British Patents No. 12,253, dated October 14, 1885, and No. 9,043, dated June 5, 1887,) of which the following is

10 a specification.

The object of my invention is to produce ropes or round bands of great gripping power and tensile strength for motive-power driving and hauling purposes. This object I attain 15 by forming composite ropes or round bands from cotton, canvas, or equivalent strong woven fabrics, by preparing or treating the fabric in the web with gutta-percha solution on both its surfaces, as described in the specification accompanying my application, Serial 20 No. 243,902, and folding the fabric, if necessary, to form the requisite breadth and the requisite number of plies or rolls of cloth, with or without the addition of a layer or 25 layers of a tough elastic selected gutta-percha or of "balata" or gutta-percha compounds between the said plies of solutionized canvas. The webs thus impregnated with a gutta-percha solution, with or without the addition 30 of a layer or layers of gutta-percha compound, are rolled up into round bands or ropes, as hereinafter described.

In the accompanying drawings, Figure 1 shows a cross-section of the flatstrip of single 35 thickness of canvas or cloth, A, first coated on both sides with the gutta-percha solution, and preferably afterward having a thin coating of the tough elastic gutta-percha mixture or compound a^2 , rolled on one side, all prepared as hereinbefore described, and which I use for the smaller sizes of round bands—as from one-fourth inch to three-fourths inch in diameter. Fig. 2 shows a corresponding cross-section of a prepared strip of canvas, A- a^2 , which I use for the larger sizes of round 45 bands—as from three-fourths inch to two inches in diameter—this strip being coated and prepared the same as Fig. 1, but having a portion at a' as doubled up in the flat form

to be rolled up in the central part of the band, 50 while the single thickness a^2 forms the outer ring-layers to make it more round and uniform at the edge a , forming the outer longitudinal joint of the completed round band, which in either case, whether made of the 55 single or doubled canvas, have this for all the larger-sized bands alternated and attached by the layer a^2 of tough mixtures of gutta-percha, all rolled and compressed in accordance with my present improvements, as will 60 hereinafter be more fully described, and preferably with the layer of gutta-percha a^2 outside the canvas.

Figs. 1^A and 2^A, respectively, indicate in end section and side elevation a short portion of 65 a solid round band, as rolled by hand or otherwise, ready for being compressed out of the single thickness, and the double thickness of canvas, as respectively shown in Figs. 1 and 2.

Figs. 3 and 4 show a longitudinal section 70 and an end view of a metallic draw "bore" or socket, B, as secured in its draw beam or frame F, especially for drawing and compressing the smaller sizes of said round bands A' through, after they have been circumferentially rolled, while in long lengths, by hand over a long table, as shown in Fig. 1^A, or otherwise rolled and compressed in front of the draw-bore B or other shaping and compressing mechanism, such as round-groove rollers; 75 or it may be long round-grooved shaping and compressing boxes or disks made in two halves or parts.

Figs. 5 and 6 show a side and front end elevation of one arrangement of rolling-machine 85 suitable for so compressing and shaping the previously prepared and rolled bands. This machine consists of a pair of rollers, C C', working over each other with various-sized round grooves B' in them, and having their 90 spindle-journal bushes fitted in vertical slotted guides supporting side frames, D, secured together by transverse stays and to a suitable foundation or frame at a convenient height for the workmen to feed or guide the 95 previously-rolled bands, as A², Figs. 1^A and 2^A, while yet hot and plastic, into the suitable-sized grooves B', as indicated by the arrows,

over a guide-table, D D'', or, it might be, a traveling band or rollers at a convenient level on the entering and delivery side of the rollers C C'. The upper and lower rollers, C C', are geared together by spur-wheels C'', and the lower one, C, would be driven by a pulley, C², and a belt, C³, passed round it from any convenient overhead motive-power driving shaft and pulley, as arranged.

10 Figs. 7 and 8 show an end and front elevation of one construction of long round-grooved compressing and shaping box or die G G', and its compressing screw-press H. The box-die is preferably made of hard wood and in 15 two halves, with the internal compressing grooved parts, B', made of metallic tubing in two halves also, but cut and jointed on a slightly different horizontal plane from the box-frame parts G and G', so as to freely admit of the insertion of the previously-rolled band A', Fig. 2^a, either by hand or further shaped in the rolling-machine, Figs. 5 and 6, and also insure the perfect coincidence of the two parts of the pressing-tube B' when put 20 together, to prevent it making a ridge or joint fin in the round driving band A' while being compressed in the two parts B'.

Fig. 9 shows a plan of the lower half of the 25 pressing-box G, ready for inserting the rolled band, and showing its shaping-tube B' as fitted and screwed in the center of the wood part G, preferably with an outer bedding of cloth, g, between the wood box G G' and the metallic tube B', to allow of a little yielding 30 to insure the true adjustment of the two halves of the tube parts B' when their guide edges are pressed together in the screw-press H, of which there would be as many ranged along the table and compressing-box G G' as are 35 found necessary according to the length of the box or that of the round band being compressed at one time.

Referring to the drawings, to form a rope or band, I take a strip or plat-band of one 40 thickness of the canvas or fabric A, solutionized on both sides, or of the composite fabric described, having the layer a² of the elastic or tough flexible gutta-percha or gutta-percha compound, as described in reference to and 45 shown in Fig. 1, and pass it through a heating-chamber, or spread it over a heated table and roll it longitudinally or lengthwise by hand or otherwise while soft into a rope or round band, as shown in Fig. 1^a, but of the full length 50 of the band if possible—that is, for the smaller sizes of ropes or round bands. I then pull it through one, two, or more draw-bores or dies, B, with proper-sized drawing-holes, B', to compress and shape it, as shown in Figs. 3 and 4; 55 or it might run through annularly-grooved drawing rolls or rollers C C', as shown in Figs. 5 and 6, to give the rope a uniform circular cross-section. For shaping and compressing the larger-sized round bands A², as 60 shown in Fig. 2^a, these would preferably be rolled while the band was hot and the gutta-percha plastic, as before described, through 65

the annular grooves B' of suitable size in the rollers C C', as indicated in the rolling-machine shown in Figs. 5 and 6; or otherwise 70 these bands A' might be laid in the lower half of the tubular pressing-box G, Fig. 9, and have the upper half, G², placed over it, and the two put into the screw-presses H, as indicated in Figs. 7 and 8, and compressed into 75 the true circular shape of the band.

In some cases when a fin or mark is formed along the sides of the bands by either the joints of the rollers C C' or the joints of the two parts of the compressing mold or die G G', the band may be passed through the roller twice with the fin in the up-and-down direction to have it completely rolled out and smooth; or vertical rollers might be mounted in front of the horizontal rollers, which would take out all marks of the fin during the first rolling through the machine; and in like manner the band could be turned round in the molds G G', and get a second pressure to make them even and smooth and remove the mark 85 of the joint of the mold before cooling. Either before or after rolling I may superadd a thin layer of gutta-percha compound on the outer surface.

Different thicknesses of canvas or cloth, A, 90 would be used for making the different strengths or sizes of round bands A' A²; and they would preferably be rolled, as shown in Figs. 1^a and 2^a, with a hole in the center, or it might be with a flexible cord of hemp or 95 cotton; or for the larger sizes, as A² in Fig. 2^a, it might be a central round core of india-rubber or small tube of india-rubber to give greater flexibility and elasticity to the finished round bands, and preferably finished 100 with the layer of gutta-percha compound a² all round outside.

The gutta-percha or gutta-percha compound 105 employed in layers a² a², between the thicknesses of canvas A in the manufacture of 110 these ropes or round bands A' A², should be of a flexible and elastic tough character—such as the mixture of selected tough gutta-percha or of balata, which is the gum of the bullet tree, or other equivalent mixtures or 115 compounds of gutta-percha, which would give the slightly flexible and tough elastic character desired.

The object of introducing the layers of 120 gutta-percha compound a² between the single or double layers of canvas or fabric A in the 125 ropes or round bands A' is to give them flexibility and gripping-power, which cannot well be obtained by the mere use of layers of gutta-percha or gutta-percha solution with 130 the cotton cloth.

When these round bands are required for 135 the driving of power-looms or other textile machinery, or purposes where a very regular and delicate gripping and driving action is required, suitable only for the power to be transmitted, and which would slip when extra strain was brought against it, and would yet maintain its maximum gripping effect

- without glazing or slipping, I, by a further improvement, attach a layer or thickness of serge or other woolen-surface fabric on the working or gripping surface or circumference 5 of the band by passing both through in a heated state between the pressing and gripping rollers, (shown in Figs. 5 and 6 of the drawings,) or in the pressing-molds, Figs. 7 and 8.
- 10 When these ropes or round bands are to be used for hauling or other purposes—such as traces for carriages or for the drawing of agricultural implements—they would preferably be coated on the outer circumferential 15 surface with gutta-percha before being finished to preserve the canvas from the weather and from wear and tear.
- What I claim is—
1. A solid round band or rope composed of 20 flat webs of canvas or other fabric impreg-
- nated with a gutta-percha solution and rolled upon itself, substantially as set forth.
2. A composite solid round band or rope composed of alternate layers of canvas and gutta-percha compound rolled upon itself, substantially as set forth. 25
3. A composite solid round band or rope composed of alternate rolls of canvas or gutta-percha compound with a layer of cloth on the outer surface, as and for the purpose set forth. 30

In testimony whereof I have signed my name to this specification in the presence of two subscribing witnesses.

ROBERT DICK.
